UNITED STATES PATENT OFFICE

161,981

FIGURINE OR THE LIKE

Allan T. White, East Palestine, and Anthony D. Bulone, Cleveland, Ohio, assignors to Fitzpatrick Industries, Inc., East Palestine, Ohio, a corporation of Ohio

Application March 3, 1950, Serial No. 8,301

Term of patent 14 years

(Cl. D29—23)

To all whom it may concern:

Be it known that we, Allan T. White, a citizen of the United States of America, residing at East Palestine, in the county of Columbiana and State of Ohio, and Anthony D. Bulone, a citizen of the United States of America, residing at Cleveland, in the county of Cuyahoga and State of Ohio, have invented a new, original, and ornamental Design for a Figurine or the Like, of which the following is a specification, reference being had to the accompanying drawing, forming a part thereof, in which

Fig. 2 is a side elevational view thereof;

Fig. 3 is a top plan view thereof; and

Fig. 4 is a rear elevational view thereof.

We claim:

The ornamental design for a figurine or the like, as shown.

ALLAN T. WHITE.
ANTHONY D. BULONE.
